UNITED STATES PATENT OFFICE.

HARRY E. CAMPBELL, OF NEW YORK, N. Y.

MUNNION FOR FIREPROOF WINDOW-SASHES.

1,229,710.

Specification of Letters Patent. Patented June 12, 1917.

Application filed January 15, 1917. Serial No. 142,377.

To all whom it may concern:

Be it known that I, HARRY E. CAMPBELL, a citizen of the United States, residing at New York, in the county of New York and 5 State of New York, have invented a certain new and useful Improvement in Munnions for Fireproof Window-Sashes, of which the following is a specification.

The invention is a munnion for fireproof window-sashes, and consists in the construction hereinafter described, which prevents said munnion from buckling or bending when one side of the sash is more highly heated than the opposite side.

15 In the accompanying drawings—

Figure 1 is an edge view of my munnion, the glass pane being removed. Fig. 2 is a section on the line x, x of Fig. 1.

Similar letters of reference indicate like 20 parts.

My munnion comprises two parallel metal plates or bars A, B, one of which, A, is flat, and the other, B, has a struck up longitudinal rib or projection C which is secured to 25 plate A by screws D. In this way, longitudinal pockets or grooves are formed on each side of the rib C and between the plates A, B for the reception of the edges of the panes E, F which are secured in said pockets by putty, cement or other suitable binding material G.

The edges of the panes E, F and the cement preferably does not extend to said rib, so that empty spaces H are formed on opposite sides of said rib. In the rib are made 35 a number of longitudinal openings I which communicate with said spaces H.

The object of constructing the munnion, as described, with openings I and preferably 40 with the open spaces H, is to equalize the temperature of the two plates A, B, and so prevent bulging or distortion of the munnion when heat is applied to the plate B, which is on the exposed side of the sash. Metal window-sashes whereof munnions form a part, 45 are usually designed to be fire-proof—or, in other words, will not become distorted so as

to open joints by the action of a flame striking their exterior. Ordinarily such a flame would heat the plate B before it would heat the plate A, with the result that the plate B would expand more than the plate A, causing the munnion to bulge or curve. The openings I prevent this by allowing the flame or hot air from the flame to pass through them and at the same time to meet plate A, and said hot air or flame is also free to enter the spaces H. The consequence is that the two plates A and B become heated practically simultaneously, and the buckling or bulging of the munnion is thus prevented.

I claim:

1. A sash munnion, comprising two parallel metal plates, one of said plates having a struck up longitudinal rib or projection, and means for securing the other of said plates to the outer face of said rib, the said rib having a plurality of transverse openings.

2. A sash munnion, comprising two parallel metal plates, one of said plates having a struck up longitudinal rib or projection, and means for securing the other of said plates to the outer face of said rib, the said rib having a plurality of recesses on its outer face forming air passages between said face and said last-named plate.

3. A sash munnion, comprising two parallel metal plates, one of said plates having a struck up longitudinal rib or projection secured to the other plate and having transverse openings, and panes between said plates and on opposite sides of said rib, there being clearances between the inner edges of said panes and said rib communicating with said transverse openings.

In testimony whereof I have affixed my signature in presence of two witnesses.

HARRY E. CAMPBELL.
